UNITED STATES PATENT OFFICE.

CHARLES S. WINN, OF ROCKFORD, ILLINOIS.

BUTTON.

1,141,090.

Specification of Letters Patent. Patented May 25, 1915.

Application filed November 16, 1914. Serial No. 872,415.

To all whom it may concern:

Be it known that I, CHARLES S. WINN, a citizen of the United States, residing at Rockford, in the county of Winnebago and State of Illinois, have invented certain new and useful Improvements in Buttons, of which the following is a specification.

This invention relates to fabric-covered buttons such as are used on garments for the purposes of ornamentation or as fastening means or both.

One of the primary objects of my invention is to provide a button of novel construction to which a fabric-covering may be applied by any unskilled person without the use of a machine or any specially constructed tools or appliances for the purpose, and which shall clamp and hold the applied fabric tightly and smoothly over the button form so that the fabric will not become wrinkled or detached.

Another object is to so construct a button that the fabric-covering may be readily and easily removed and replaced by another covering whenever desirable.

Fabric-covered buttons are used very extensively on garments merely for ornamental purposes; and when the garments are cleaned it is necessary to remove the buttons therefrom to prevent both the buttons and the garment from being damaged. Usually the buttons are sewed to the garment, and the task of removing and replacing the buttons so attached is tedious and very unsatisfactory. In this invention I aim to provide a fabric-covered button which may be detachably connected to a garment so that the operation of resewing the button to the garment when the button is reattached is eliminated. I also aim to provide a detachable button of the above character which shall be so constructed that the act of removing the button from a garment partially disassembles the button itself, and in which the operation of attaching the button draws the fabric-covering tightly over the button form and holds it securely in position thereon. Thus the button may be quickly detached either for the purpose of removing it from the garment when the same is being cleaned or for changing the fabric covering of the button.

Another object of my invention is to provide a fabric-covered button of the removable fabric type which, while readily detachable from the garment, is securely at

tached to the garment so as to be capable of use as attaching means as well as being ornamental.

A further purpose of my invention is to provide novel means for detachably connecting a fabric-covering to a button body so that coverings of various materials having varying thicknesses may be applied and drawn over the form of the button and secured thereto with equal facility, and which prevents improper fastening of the fabric to the button body, such as might be caused by bunching of the material at the underside of the button or by the use of unduly thick material.

Another object is to provide a fabric-covered button having a detachable screw-member provided with an eye adapted to be sewed to the garment, and to provide means for preventing the button from turning relatively to the screw during use, thereby insuring that the button will not become loosened from its fastening means.

Other objects of my invention will be apparent as the same becomes better understood by reference to the following description when considered in view of the accompanying drawings, wherein:

Figure 1 is a face view of a button embodying my improvements; Fig. 2 is a back view of the button showing a portion of the removable back-member broken away; Fig. 3 is a view of the back-member removed from the button; Fig. 4 is a sectional view as taken on the line 6—6 of Fig. 1, but showing several parts of the button disassembled and illustrating the fabric as it is first applied to the button body; Fig. 5 is a similar sectional view, but with the parts assembled, although not in final operative position, and Fig. 6 is a sectional view showing the parts in operative position.

Referring more particularly to the sectional views of the drawing it will be observed that the body or form of the button designated generally by the reference character 7, is of concavo-convex form. I have found it preferable to construct the button form of wood, although other materials such as celluloid, rubber or metal may be used in its construction. The convex side 8 of the body forms the face side of the button and the concave side 9 forms the back and is provided with a raised center portion or boss 11 in which is formed a threaded socket 12. The rim of the button is curved cross

sectionally as is indicated at 13 whereby the front and back surfaces of the button are joined without any abrupt angles or edges.

The fabric-covering designated by the reference character 14, with which it is desired to cover the face of the button, may be of any suitable material. When a piece has been selected it is cut circular in form with a diameter greater than that of the button body so that when arranged on the body to cover the face 8 thereof the edge portion of the fabric-covering will be folded over the rim of the button to extend within the rim at the back of the button but with the edges of the fabric terminating short of the central boss. The edge portion of the fabric is then gathered by a shirr or draw string 15 and drawn together, the ends of the string being then tied or fastened to the fabric to prevent withdrawal of the string. The fabric-covering as thus applied is shown in Fig. 4, and it will be apparent that with this construction, although the fabric is held on the button body by the shirr string drawing the edge portion of the fabric together, the fabric is not positively secured to the body so as to insure against wrinkling of the fabric both on the face of the form and at the rim thereof. I have provided means for positively drawing the fabric-covering smoothly and tightly over the face of the button body and for securely holding the fabric-covering in connection with the body, which means will be now described.

A disk-shaped member 16, preferably formed of sheet metal is adapted to form the button back. The disk is smaller in diameter than the body 7 so that it may be inserted within the peripheral edge 13 of the body as shown in Fig. 4. The disk back-member is provided at its center with an aperture 17 through which a screw 18 is adapted to be inserted and to be screwed into the threaded socket 12 for the purpose of drawing said back-member into operative position. The screw is provided with a head 19 in the shape of an eye, the head being adapted to abut against the outer side of the disk member 16 to effect the drawing up of said disk. When the screw is threaded into the socket 12 the edges of the disk will be drawn inwardly along the inclined rear faces of the body thereby drawing the fabric tightly over the front face and edges of the body. The shirr* string which holds the edges of the fabric from separation under tension and prevents slippage of the fabric away from the body back, insures that the fabric will be drawn taut over the body by the clamping action of the disk and precludes any liability of the fabric becoming bunched or wrinkled over the edges of the body. It will be seen from Figs. 4 and 5 that the disk back-member is dished. The button is assembled with the convex face of the disk

disposed outwardly and the disk will retain its dished shape until the fabric is drawn taut as shown in Fig. 5. Upon further tightening of the screw 18, the disk back-member will be drawn to a comparatively flat plane as shown in Fig. 6, thereby forcing the rim of the disk back-member outwardly to positively clamp the fabric to the button body. In fact, the fabric will be slightly impressed into the said body thereby insuring against its being released.

The button constructed and assembled as above described is now ready to be attached to a garment, and by the provision of the screw with an eye the button may be either sewed to the garment or attached by means of a spring clip. The more ordinary method of attaching is by sewing the eye to the garment, thus permanently attaching the eye, but by a detachable spring clip the eye may be detached at any time together with the button. In order to prevent the body from becoming loosened from the screw-member 18 by turning upon the screw when in operative position I have provided a plurality of recesses 21 in the outer side of the disk back-member extending from the aperture 17, the recesses being adapted to receive the inner end of the screw-head 19. This construction affords a yielding lock which requires, before the button can be removed, sufficient twisting pressure to spring the disk back from connection with the head of the screw. Although I have shown the recesses arranged quartering, it is obvious that but a single pair of diametrically oppositely disposed recesses might be employed.

From an inspection of Fig. 6, it will be noted that when the disk member is moved to its operative position a space designated by the reference character 22 is left between the disk member and the boss 11 of the button body, and that only the rim of the disk back-member is drawn into engagement with the button body as described above. This provision in the construction has been made so that fabrics of various thicknesses may be used without requiring disk back-members of various sized diameters, and for the purpose of insuring that the disk member will always draw the fabric taut and lock the fabric securely to the button body regardless of the thickness of the fabric. A further purpose of this construction is to insure that the disk back-member be drawn properly to operative position, and may not, by chance, be prevented by an edge portion of the fabric becoming interposed between the boss 11 and the disk back-member.

When it is desired to temporarily remove the button from the garment the button would be unscrewed from the screw-member 18 thereby partially disassembling the button since the disk back-member 16 is disconnected from the button body. The button

being thus detached, the fabric-covering thereof may be removed from the body for purposes of cleaning or replacement by a new fabric-covering. It is obvious that the 5 fabric-covering may be detached by simply cutting the shirr string 15. It will be noted that when the button is removed either for the purpose of changing the fabric or for detaching the button when the garment is being 10 cleaned, the screw-eye member remains permanently attached to the garment and to remove the button it is only necessary to thread the body on to the screw-member.

From the foregoing it will be apparent 15 that I have provided a fabric-covered button of such construction that the fabric-covering may be readily and easily applied to and detached from the button body; and that these operations necessitate no skilled labor 20 or endeavor, but may be performed by any ordinary person. It will also be seen that when the fabric is attached to the button body it is held very firmly in connection therewith, drawn taut over the face of the 25 body, and that there is very little, if any, possibility of the portion of the fabric at the rim of the button becoming loosened and wrinkled.

I claim:

30 A button comprising a circular body member shaped to provide a convex front face and a concave rear face having a centrally

disposed, rearwardly projecting boss provided with an internally threaded bore, a fabric covering disposed over the convex 35 face of said body and turned inwardly over the periphery thereof, the free edges of the fabric being gathered and drawn inwardly across the rear face of the body member toward said central boss, means for holding 40 the free edges in position so as to maintain the covering drawn smoothly and tightly over said convex face, a back member comprising a disk of resilient material shaped to fit within the concave rear face of the body member and provided with a centrally disposed aperture, and means passed through said aperture and threaded into said socket for drawing said disk inwardly toward said 50 boss to firmly clamp the fabric between the perimeter of the disk and the surrounding concave wall of the body member and positioning the disk entirely within the body member so that the covered edges of the body member project rearwardly beyond the disk 55 to protect a garment from contact with the disk, said means being provided rearwardly of the disk with an eye whereby the button may be attached to such garment.

CHARLES S. WINN.
